UNITED STATES PATENT OFFICE.

HENRY K. SHANCK, OF ARCANUM, OHIO.

VIBRATING PROPELLER.

SPECIFICATION forming part of Letters Patent No. 224,233, dated February 3, 1880.

Application filed August 13, 1879.

To all whom it may concern:

Be it known that I, HENRY K. SHANCK, of Arcanum, in the county of Darke and State of Ohio, have invented certain new and useful 5 Improvements in Vibrating Propellers, of which the following is a specification.

My invention relates to a novel construction and arrangement of direct-acting submerged propellers applicable to ships and boats, and 10 is especially adapted for canal-boats, its main object being to produce a proper speed in the boat with a minimum degree of power, and without creating a lateral wash of the waters, which will damage the banks.

15 The propeller belongs to the general class known as "duck's-foot propellers," and according to my invention consists of a practically horizontal double shaft, or two shafts connected by a cross-bar, having imparted to it a longitudinal reciprocating motion, and having secured to its outer end or ends one or more pivoted or hinged wings normally, and during the inward movement of the shaft standing edgewise in the line of travel of the craft, but 20 during the outward stroke of the shaft standing at a greater or less angle to its normal position and approximately flatwise across the line of travel, so as to act flatwise against the water and deliver an effective propulsive stroke 25 for impelling the boat forward. When two wings are used they approach each other and lie flatwise nearly or quite parallel during the inward stroke, but diverge and stand nearly or quite edge to edge during the outward stroke. Suitable stops are arranged to limit 30 the vibratory movement of the wings. The direct stroke in the line of travel of the boat produces comparatively little lateral wash.

35 The motive device of the propeller consists 40 of a spring walking-beam connected to the inner end of the shaft by a suitable link and deriving a vibratory motion from a steam-engine or other motor. When a propeller is driven outward by the walking-beam the elasticity of 45 the latter prevents the wings from simply violently displacing the water, and thereby losing their most effective propulsive force, and permits them to, as it may be said, take hold of the water from the start. The elasticity of 50 the beam also obviates the jar of the boat which would occur at the beginning of both

outward and inward strokes, but especially at the beginning of the former, were the beam rigid.

In the accompanying drawings, Figure 1 55 represents a horizontal sectional view of the stem of a boat provided with two propellers according to my invention: Fig. 2 is an end view of the wings of the propeller as they stand during the outward stroke, and Fig. 3 is a 60 view of same as they stand during the inward stroke and oppose the least resistance to the play of the shaft.

The letter A indicates the two double shafts, 65 arranged to play longitudinally through suitable bearings B in the stern-wall C of the boat, and also through other bearings, D, which should be properly arranged and supported within the boat. Each of the double shafts A is composed of two parallel single 70 shafts or arms, a, connected firmly at their inner ends by a cross-bar, a', and rigidly secured at their outer ends to a cross-head, E. This construction of the propeller-shaft is used in order to prevent any tendency to rotary 75 motion or torsional strain, and to hold the wings truly in their most effective plane of movement.

To the outer edge of each cross-head E are 80 hinged the wings F by means of hinge-straps g fastened to said wings, similar straps g' fixed to the cross-head, and a pintle-rod, f, passing through the tubular portions of all said straps and having its ends secured in sockets in rearward extensions e of the cross-heads, in order 85 that said rod may be firmly supported. These rearward extensions e are bent inwardly to form stops e', which limit collapsing movement of the wings, and from the opposite sides of the cross-head project other stops, h, 90 which limit the expanding or diverging movement of said wings.

The letter K designates the spring walking-beam, composed of the rigid central portion, k, and the elastic extensions or end portions, L, preferably formed by firmly bolting 95 to the central rigid portion a bar of spring-steel of proper length; or the elastic extensions may each be composed of several leaves of spring-steel arranged in any known and 100 suitable manner for forming springs.

The ends of these elastic portions of the

walking-beam are connected by suitable links *m* to the cross-bars *a'* of the propeller-shafts, and one end of the rigid portion *k* of the walking-beam is pivoted to the piston-rod *n* of a 5 steam-engine, the cylinder *N* only of which is shown.

In an arrangement such as shown in the drawings, when the piston-rod is connected directly to the walking-beam the cylinder 10 should oscillate, as in the ordinary oscillating engine; but an engine with stationary cylinder may, of course, be used, and the piston-rod connected to the walking-beam through what are known as "parallel-motion links."

15 It is obvious that on the initial movement of the beam to drive either shaft outward the elastic extension will yield slightly and cause the shaft to gradually attain its full speed, thus preventing the jar which would be given 20 to the boat were the beam and its connections with the shaft rigid, so that the wings would be caused to strike the water with full force at the start.

Another very great advantage of the elasticity of the beam is that the propeller is not forced suddenly through the water, displacing it without producing a due effect upon the boat, but is caused to move in such manner against 25 the water as to produce a maximum propul-

sive effect upon the boat in relation to the displacement of water occasioned.

Instead of providing the walking-beam with elastic extensions, as shown in the drawings, said beam may be made rigid its entire length and have its ends connected to the propeller-shafts by elastic links, such as strong helical or elliptic springs secured to pivoted heads or links, or connected to the beam and propeller-shaft in any other suitable manner.

From the opposite sides of the boat I extend guards *O* rearwardly beyond the position of the propeller-wings when in line, for the purpose of protecting said wings from injury in passing through canal-locks.

What I claim is—

The combination, with the cross-head *E*, carrying the vibrating wings *F*, the reciprocating shafts *B*, and the spring walking-beam *K*, having flexible connections *L*, secured to the shafts respectively by means of suitable 50 links, substantially as specified.

In testimony that I claim the foregoing I have hereunto set my hand in the presence of the subscribing witnesses.

HENRY K. SHANCK.
